UNITED STATES PATENT OFFICE.

JOHN T. SMITH, OF MOUNT AIRY, MARYLAND.

REVERSIBLE CONCRETE GUTTER AND DRAIN BLOCK.

1,176,611.

Specification of Letters Patent. Patented Mar. 21, 1916.

Application filed September 30, 1915. Serial No. 53,300.

To all whom it may concern:

Be it known that I, JOHN T. SMITH, a citizen of the United States of America, residing at Mount Airy, in the county of 5 Carroll, in the State of Maryland, have invented certain new and useful Improvements in Reversible Concrete Gutter and Drain Blocks, whereof the following is a specification.

10 The object of this invention is to provide in a single article of manufacture a concrete block which can be cheaply manufactured and placed on the market and used by farmers, dairymen, householders and other consumers, without the aid of skilled labor, in the construction of gutters, blind ditches, drains and for other purposes, the article being adapted for either the bottom of the 15 gutter or drain, or for the cover thereof.

20 Figure 1 of the accompanying drawings represents a perspective view of a concrete block embodying this invention in position to form a gutter or the bottom of a drain, a part being broken out. Fig. 2 represents 25 a perspective view thereof in position to form the top or cover of a closed drain. Fig. 3 represents a perspective view of a series of cow stalls and a gutter constructed from these blocks disposed along the ends 30 thereof. Fig. 4 represents a longitudinal central section of a fragment of a gutter constructed from these concrete blocks. Fig. 5 represents a perspective fragmentary view 35 of a landscape showing a surface gutter constructed from these blocks and a cover or culvert therefor also composed of these blocks inverted position at the crossing of a roadway. Fig. 6 represents a perspective fragmentary view of a landscape showing a

40 plain surface gutter provided with a cover or culvert at a roadway intersection, said cover or culvert being composed of a series of these blocks in reversed position mounted directly on the clay or earth. Fig. 7 represents a longitudinal section of a barn or 45 house gutter and a closed outer drain in continuance with said gutter. Fig. 8 represents a longitudinal section of a barn or house gutter and a closed outer drain in continuance with said gutter, the earth forming 50 the bottom of said drain.

The same reference numbers indicate corresponding parts in the different figures.

A block 10 molded of concrete or reinforced concrete constitutes an article of man-

ufacture embodying this invention and adapted for either under or over use as described or conjunctively for both the under and over use to form gutters, drains, culverts and the like. This block comprises a 60 rectangular horizontal central portion 11, two angular portions 12 and 13 integral with the outer ends of said central portion and inclined outward therefrom and two horizontal outward extensions 14 and 15 integral with said inclined portions. The outer faces 16 and 17 of the inclined or angular portions 12 and 13 form braces which tend to hold the blocks against lateral displacement and the outer faces 18 and 19 of the 70 horizontal extensions 14 and 15 provide broad bearing surfaces which hold the blocks or slabs against vertical displacement. The horizontal central portion 11 is provided on one edge adjacent to its outer face with a 75 rib or tongue 21 and along its opposite edge adjacent to its inner face with a rib or tongue 22. This horizontal central portion 11 is also provided on one edge adjacent to its outer face with a recess 23 corresponding in depth to the rib or tongue 21 and along its opposite edge adjacent to its inner face with a recess 24 corresponding in depth to the rib or tongue 22. These ribs interlock with each other and with said recesses 80 when the blocks are in alinement to form a gutter, a drain or cover therefor.

85 In the use of these blocks to form an open channel or gutter, they are set in the earth, floor or other place, side by side, with their central portions downward as illustrated in Fig. 3 and at the opposite ends of Fig. 5. In forming a closed channel or drain they are placed side by side with their central portions 11 upward as indicated in the central portion of Fig. 5 and in Fig. 6.

90 When the blocks are laid to form a drain, the central flat portions 11, the outwardly flaring angular portions 12 and 13 and the horizontal outward extensions 14 and 15 afford horizontal bearings in two different planes and intermediate inclined bearings, said several bearings coöperating to hold the blocks in normal position in the drain, and the outward horizontal extensions of the 100 bottom blocks and cover blocks meet face to face and afford large contact bearing surfaces which tend to hold the cover in position on the bottom of the drain.

105 This single structure is readily adapted to 110

the various parts of a drainage scheme, is cheaply manufactured, can be set up without skilled labor and forms a gutter or drain of great durability.

5 I claim as my invention:

1. An article of manufacture consisting of a reversible concrete gutter and drain block adapted to form a section of the bottom or top of a channel or conduit and comprising 10 a horizontal central portion, angular portions integral therewith at opposite ends thereof and horizontal outward extensions integral with said angular portions, said horizontal central portion being provided on 15 its opposite edges with ribs and recesses adapted to interlock with corresponding recesses and ribs of adjacent blocks when placed in alinement therewith to form the bottom or top of a gutter or drain.
- 20 2. An article of manufacture consisting of a reversible concrete gutter and drain block adapted to form a section of the bottom or top of a channel or conduit and comprising a horizontal central portion, angular portions integral therewith at opposite ends thereof and horizontal outward extensions integral with said angular portions, said horizontal central portion being provided on 25 its opposite edges with ribs in different planes and with recesses in different planes adjacent to said ribs and adapted to 30 interlock with corresponding recesses and ribs of adjacent blocks when placed in alinement therewith to form the bottom or top 35 of a gutter or drain.
3. A drain having a bottom composed of a series of concrete blocks, each comprising a horizontal central portion, angular portions integral therewith at opposite ends 40 thereof, and horizontal outward extensions integral with said angular portions, said central portion being provided on its opposite edges with ribs and recesses which inter-

lock with corresponding recesses and ribs of the adjacent blocks.

4. A covered drain comprising a bottom composed of a series of drain blocks each comprising a horizontal central portion, angular portions integral therewith at opposite ends thereof and horizontal outward extensions integral with said angular portions, said central portion being provided on its opposite edges with ribs and recesses interlocking with corresponding recesses and ribs of adjacent blocks, and a cover composed of 50 a series of blocks corresponding in structure and relation with the blocks of said bottom and disposed in inverted position over said bottom blocks.

5. A drain comprising a bottom composed 60 of a series of drain blocks each having a central flat portion, outwardly flaring angular portions integral therewith at opposite ends thereof and horizontal outward extensions integral with the upper ends of said 65 outwardly flaring angular portions, said central flat portion and horizontal extensions affording horizontal bearings in two different planes and inclined intermediate bearings between said horizontal bearings, said 70 several bearings coöperating to hold said blocks in normal position in the drain, and a cover composed of a series of blocks corresponding in structure and relation with the blocks of said bottom and disposed in 75 inverted position over said bottom blocks, the outward horizontal extensions of the bottom blocks and cover blocks meeting face to face and serving as contact bearing surfaces for holding said cover in position on 80 said bottom.

JOHN T. SMITH.
